UNITED STATES PATENT OFFICE.

WILLIAM E. BAILEY, OF BEVERLY, MASSACHUSETTS, ASSIGNOR TO ARBETTER FELLING MACHINE COMPANY, OF BOSTON, MASSACHUSETTS, A CORPORATION OF MAINE.

BLINDSTITCH SEWING-MACHINE.

1,180,368.

Specification of Letters Patent. Patented Apr. 25, 1916.

Application filed November 5, 1909. Serial No. 526,372.

To all whom it may concern:

Be it known that I, WILLIAM E. BAILEY, a citizen of the United States, residing at Beverly, in the county of Essex and State 5 of Massachusetts, have invented an Improvement in Blindstitch Sewing-Machines, of which the following description, in connection with the accompanying drawing, is a specification, like letters on the drawing 10 representing like parts.

This invention relates to a sewing machine for felling with blind stitches and is an improvement in the Arbetter type of blindstitching machine.

15 The invention relates particularly to an improved means for presenting the work to the stitch-forming mechanism.

20 The stitch-forming mechanism and the main portion of the machine is of the construction hitherto employed in the Arbetter type of blindstitch sewing machine, but the feeding mechanism proper is of the type which operates entirely upon the upper surface of the goods.

25 While the machine of this invention is useful for felling a variety of work, it is particularly designed for use in connection with work having inequalities, such as cross seams, which must pass between the instrumentalities acting upon the upper and lower surfaces of the work in the vicinity of the stitching point, and in which the felling is performed over such irregularities.

30 The invention provides in connection with 35 an upper stationary presser foot and an upper feed mechanism a vertically yielding work-support and an independently mounted vertically yielding lower presser, the latter of which maintains the work in engagement with the upper presser and feed, and the former of which supports the work in the vicinity of the stitching point and enables the work to be properly handled.

35 The invention also involves the additional 45 feature of a pivoted plate forming the upper surface of the lower presser, and so constructed that the usual bender employed in this type of machine has its movement through an opening in said pivoted plate 50 in line with the pivotal axis thereof. This construction enables the work at all times to be held firmly between the lower presser and the upper presser and feed at the point of entrance of the needle into the fabric, notwithstanding the passage of irregularities, 55 such as cross seams, therebetween, so that

the felling stitches may have the same relation to the felled edge of the work at the points where these irregularities occur, as well as at other points. 60

The invention will more fully appear from the accompanying description and drawings and will be particularly pointed out in the claims.

The drawings represent so much of a 65 blindstitch felling machine as is necessary fully to disclose the said invention.

In the drawings, Figure 1 is a front end elevation of the lower portion of the machine. Fig. 2 is a front elevation in detail 70 of the upper end of the bender and of the lower presser showing the pivoted plate form. Fig. 3 is a plan view of the construction shown in Fig. 2. Fig. 4 is a side elevation of the parts shown in Fig. 1, Fig. 5 is 75 a top plan of the lower presser shown in Figs. 1 and 4.

The stitch-forming mechanism and correlated parts, the bender mechanism and the general arrangement of the machine, except 80 for the feeding mechanism and work-supporting devices, are constructed substantially the same as in the machine illustrated and described in the Arbetter Patent No. 1,152,871 granted September 7, 1915, and 85 the feeding mechanism herein partially illustrated is substantially the same as that illustrated in the patent to Bailey, No. 1,091,619 granted March 31, 1914, and it will be unnecessary, therefore, to enter into 90 any detailed description of the machine as to these features.

The lower portion of the overhanging arm of the machine is indicated at A. The presser-foot D is stationary and is mounted 95 in the overhanging arm. At its lower heel portion it is constructed to present a guide D² for the edge of the superimposed layer or layers of fabric, and at its toe portion it is provided with the usual guard-plate D³. 100 The portion of the presser foot riding over the superimposed layer or layers of fabric presents the usual beveled extension D¹² to guide the fabric therebeneath.

The stitch-forming mechanism, of the 105 usual Arbetter type, is represented in Fig. 1 and comprises the curved reciprocating needle and the coöperating rotary hook. The curved needle is shown at a² mounted in a needle-carrier b' mounted on the shaft B⁷ and oscillated by means of a link B² connected to a crank arm. The shaft B⁷ is sup-

ported in the bearing in the vertical rocker-shaft B^{10} . The needle is thus given its reciprocations in diverging planes to make the felling stitch. The complementary stitch-forming mechanism is shown as a rotary hook and inclosed bobbin case a^2 carried by the support A^8 depending from the overhanging arm A .

The feeding mechanism is mounted and 10 operates entirely above the work and acts therefore solely upon the upper surface of the work. It comprises a suitably constructed feed dog E and means for giving it an up-and-down and a forward and backward 15 movement. In the form illustrated a member E^2 is mounted to slide vertically in the arm A , and this sliding member E^2 carries an elongated transverse bearing E^5 in which is fulcrumed a bell-crank lever E^6 , one end 20 of which carries the feed dog and the other end of which is operated by a suitable connection with the driving mechanism.

The work table of the machine is indicated at E^{21} and is apertured beneath the stitch-forming and feeding mechanism to provide for the work-support E^{22} and the lower presser E^{23} . The work-support E^{22} supports the body of the work adjacent to and beneath the stitch-forming and feeding mechanisms so as to maintain it in proper position, but the immediate portion acted upon by the feed and the needle is directly supported by the lower presser E^{23} . These elements are limited in their upper positions, the 35 former by a stop E^{40} and the latter by contact with the work against the stationary presser-foot D , so that all irregularities, such as cross seams, may readily pass over the work-support E^{22} beneath the parts carried by the over-hanging arm, and still 40 present the work in proper relation to the stitching and feeding instrumentalities, while the lower presser E^{23} directly supports and handles the work at the stitching 45 point. The bender L , by means of which in this type of machine the main or base layer of fabric is projected into the path of the needle, passes up through an aperture in the lower presser E^{23} . It operates upon each 50 movement of the needle for forming the stitch in the single or base layer to project the material into the path of the needle. This bender L is carried by a bender-support L^2 mounted to slide vertically in bearings L^3 55 in the face plate E^{20} which is fastened to the work support stand by suitable screws E^{210} . The bender is given its vertical movement by means of a stud L^4 acting between projections on the bender-support and carried by 60 a rocker-arm L^5 mounted on the rock shaft L^6 , which is provided at its opposite end with the arm L^7 acting against the cam L^8 carried by the bender-shaft L^9 . The work support E^{22} is carried by the vertically moving 65 work support stand E^{50} , and this stand

is retained in the vertical ways in which it slides by means of a face plate E^{20} . The work support E^{22} with its supporting stand E^{50} is normally held in elevated position by the spring E^4 , and it is depressed by the engagement of a suitable lever (not shown) with the stud E^8 .

The lower presser E^{23} is clamped by a set screw E^{24} to its supporting post E^{25} . The post E^{25} is mounted to slide vertically in 75 bearings formed in the face plate E^{20} . A screw E^{26} secures a collar E^{27} to the post E^{25} , and this collar serves as an abutment for the coil spring E^{28} surrounding the post. The lower end of the spring abuts against the 80 vertically adjustable bushing E^{29} by means of which the tension of the spring may be varied and the consequent upward pressure of the lower presser E^{23} adjusted. The stud E^{501} on the collar E^{27} extends into a slot 85 E^{30} in the work support stand, and prevents rotation of the post E^{25} . A stud E^{31} projects outwardly from the work support stand in the path of the stud E^{501} , and is so arranged that upon the depression of the work support to a predetermined extent, it will engage the stud E^{501} , and then upon further depression of the work support, the lower presser will likewise be depressed.

The lower presser, shown in Figs. 1, 4 and 95 5, is provided with a suitable aperture T for the passage of the bender L , and is cut away at T^2 to relieve the friction on the material as it passes to the stitch-forming mechanism. The construction of the lower presser, illustrated in Figs. 2 and 3, is however the preferred form, and enables the work at all times to be held firmly between the lower presser and the upper presser and feed at the stitch-forming point, allowing the passage of all irregularities, such as cross seams, therebetween, without effecting the successful formation of the stitches. In this form the lower presser comprises a base plate I provided with a socket secured to the post 100 E^{25} by the set screw R^4 . Upon this face plate is pivotally mounted the presser plate R^2 . Both the face and presser plate are apertured at R^3 to permit the passage of the bender and the pivots R^4 upon which the 105 pivoted presser plate swings are arranged to have their axes intersect the vertical axis of the bender. The pivoted presser plate is beveled or sloped away in both directions in the line of feed from the pivotal point so 110 that normally the area of the material clamped between the lower presser and the upper presser and feed is just sufficient to secure the proper results. Any irregularity, such as a cross seam in the material, as it approaches and passes the stitching point will 115 cause the pivoted presser plate to rock upon its pivot and thus preserve the proper relation between the material and the stitch-forming mechanism to insure the proper po- 120 125 130

sitioning of the stitches in the material during the passage of the irregularity in the material.

In both forms of lower pressers the work is maintained in engagement with the upper presser and feed by the vertically yielding lower presser at and adjacent to the stitching point while the body of the work is supported by the yielding work support immediately surrounding the lower presser without being forced into contact with the upper presser and feed. Thus the work is easily handled and its ready presentation to the stitch-forming mechanism at all times is secured.

Having fully described my invention, what I claim as new and desire to secure by Letters Patent is:—

1. A blind stitch sewing machine, comprising in combination, feeding mechanism, a stationary presser foot, a vertically movable work support, a vertically yielding lower presser, independent of said feeding mechanism and connections between the work support and the lower presser allowing independent upward movement of each but causing the depression of the lower presser upon the depression of the work support beyond a predetermined distance.

2. A blind stitch sewing machine, comprising in combination, feeding mechanism, a stationary presser foot, a vertically movable work support, a vertically yielding lower presser independent of said feeding mechanism but coöperating therewith, a stop for limiting upward movement of said work support, and connections between the work support and the lower presser allowing independent upward movement of each but causing the depression of the lower presser upon the depression of the work support beyond a predetermined distance.

3. A blind stitch sewing machine, comprising in combination, a stationary presser foot, a vertically movable work support, a vertically yielding lower presser mounted independently of the said work support, and connections between the work support and the lower presser allowing independent upward movement of each but causing the depression of the lower presser upon the depression of the work support beyond a predetermined distance.

4. A blind stitch sewing machine, comprising in combination, a stationary presser foot, a vertically movable work support, a vertically yielding, movable lower presser, a presser plate pivotally mounted upon said lower presser, stitch forming mechanism mounted and operating above the work support, and acting to form stitches in the material above the pivotal axis of said plate.

5. A blind stitch sewing machine, com-

prising in combination, a stationary presser foot, a vertically movable work support, a vertically yielding, movable lower presser, a presser plate pivotally mounted upon said lower presser, stitch forming mechanism mounted and operating above the work support, a vertically movable bender, and means for moving the bender in the path transversely of the pivotal axis of said presser plate.

6. A blind stitch sewing machine, comprising in combination, feeding mechanism, a stationary presser foot, a vertically movable work support, a vertically yielding lower presser independent of said feeding mechanism but coöperating therewith, connections between the work support and the lower presser allowing independent upward movement of each but causing the depression of the lower presser upon the depression of the work support beyond a predetermined distance, a stop for limiting the upward movement of the work support, stitch forming mechanism mounted and operating above the work support and co-acting with the lower presser.

7. A blind stitch machine comprising a curved oscillating needle and complemental stitch forming mechanism and feeding mechanism mounted and operating above the work support, a vertically movable work support, a vertically yielding lower presser, connections between the work support and the lower presser allowing independent upward movement of each but causing the depression of the lower presser upon the depression of the work support beyond a predetermined distance.

8. A blind stitch sewing machine, comprising in combination, a stationary presser foot, a vertically movable work support, a vertically yielding lower presser, connections between the work support and the lower presser allowing independent upward movement of each but causing the depression of the lower presser upon the depression of the work support beyond a predetermined distance, a stop for limiting upward movement of the work support, stitch-forming mechanism mounted and operating above the work support, a presser plate pivotally mounted upon the lower presser, and feeding mechanism mounted and operating above said pivoted plate and co-acting therewith.

In testimony whereof, I have signed my name to this specification, in the presence of two subscribing witnesses.

WILLIAM E. BAILEY.
